AWNINg WINDOW OPERATING DEVICE

Joseph C. Bancroft, Jamestown, N.Y.

Application June 17, 1948, Serial No. 33,581

2 Claims. (Cl. 263—106)

1

This invention relates to window sashes of the so-called "awning" type, wherein the sash is pivoted in the window frame on horizontally-disposed pivots at the sides of the sash near the upper edge of the sash, and the present improvements have reference to sash-operating means by which such a sash, or a plurality of sashes mounted one above the other and coupled together, can be smoothly, easily and conveniently moved to open, closed or intermediate positions.

In most of the devices proposed for use in connection with awning sashes of this character, gearing, links, levers and arms and other complex devices are employed to such an extent as to make the cost of manufacture, installation and maintenance very considerable, not to mention the fact that such devices possess the likelihood of failure of satisfactory operation, particularly after some use.

The present invention, therefore, contemplates the provision of a greatly simplified and inexpensive sash-operating device having a minimum of parts, and those employed being of sturdy construction so that an assurance of long life, smooth operation and general satisfaction is had.

More particularly, the invention contemplates the provision of a crank-operated plate or disk contained in a suitable housing secured to the window frame in a convenient position for operation within the room, said plate or disk being pivotally attached to one end of a link which has its other end connected by a ball-and-socket connection to a slide mounted for slidable movement back and forth in a suitable guide channel provided on the lower edge of the sash. The sash so connected to the operating means as above described may, if desired, be coupled by suitable connecting links to a plurality of other sashes arranged above it so that the several sashes will be simultaneously opened or closed by manipulation of said operating means.

These and other objects are attained by the invention, a more particular description of which will hereinafter appear and be set forth in the claims appended hereto.

In the accompanying drawings, wherein an illustrative embodiment of the invention is disclosed:

Fig. 1 is a vertical sectional view through a sash and frame therefor, showing the improved operating device;

Fig. 2 is a top plan view of the outer end of the sash-operating link or arm;

Fig. 3 is a vertical sectional view through said

2

end of the arm or link and the guide in which it is slidable;

Fig. 4 is a view of the under side of the structure shown in Fig. 3;

Fig. 5 is a top plan view of the operating device, with parts broken away, and other parts in section, to disclose construction;

Fig. 6 is a top plan view of the rotative actuating member or plate, showing the pivotal attachment of one end of the operating link thereto, and

Fig. 7 is an edge view of said operating member, looking at the right edge of Fig. 6.

The sash of the character to which the present invention is applicable is provided with a frame 1 which may be of metal or wood construction, and it includes spaced vertical side bars 2, one of which is shown in Fig. 1 connected in the known manner at the top and bottom by horizontal bars,

the bottom one of which is shown at 3. At 4 is shown one of the sashes pivotally mounted in the frame, said sash being of rectangular form and having the side bars 5, upper cross bar 6 and lower cross bar 8. The conventional glass pane is omitted from the frame to simplify illustration. At the opposite ends of the upper cross bar 6 are the pivots 7 for the sash and which pivotally mount it in the frame, said pivots being disposed horizontally, permitting the sash to swing outwardly to open position, substantially as shown in Fig. 1. By means of the operating device to be described, the sash can be opened or closed or moved to and maintained in any desired intermediate position.

The sash shown at 4 is the lowermost sash in the frame 1, and a plurality of additional sashes pivotally mounted as described, are usually arranged in tandem or one above the other within the frame 1. The several sashes so mounted are

coupled together so that when the lowermost sash is moved by the operating device, the other sashes are simultaneously moved to a similar position. The several sashes are coupled together at their ends by links, a portion of one of said links being shown at 20 in Fig. 1, said links being pivotally attached as at 21 to lugs 22 projecting from the several sashes. This coupled arrangement of the sashes is known in this art, and sashes arranged in the manner thus far described, are known as "awning windows."

The improved operating device includes an arcuate housing 10 provided at its opposite ends with ears 25 through which screws 11 extend to fasten the housing 10 to the vertical flange 12 of the bottom bar 3 of the window frame. Ro-

tatively mounted on a vertical pivot 26 and within the housing is a disk-like plate 14 provided with an arcuate slot 23, having a toothed edge 29 constituting a rack for engagement by a pinion not shown, but located within the housing and mounted on the end of the crank 13. This structure is known in window-operating devices.

At 16 is shown an arm or link which is pivotally connected at 15 to the plate 14, said pivot 15 being a horizontal pivot allowing the arm or link 16 to swing up and down to an extent required by movement of the sash 4, as will be hereinafter explained. At its outer end, the arm or link 16 is slightly offset and is provided with a ball or sphere 17 that is received in a socket 19 provided on a plate 18 constituting a slide. Said slide 18 is slidably mounted in a channel-shaped guide member 9 secured to and extending along the lower edge of the bottom cross bar 8 of the sash frame 4. This arrangement is such that the outer end of the arm or link 16 is slidably coupled to the lower edge of the sash 4 and by means of the ball-and-socket coupling between the end of said arm or link 16 and the slide 18, a universal pivotal connection is established between the link 16 and the bottom of the sash. It will be noted that the housing 10 is open at its forward end, as indicated at 32, and the flange 12 is cut-away or slotted as at 33, to permit rotative movement of the plate 14.

From the foregoing, the operation of the improved sash-operating device will be readily understood. By rotation of the crank 13, the plate 14 will be rotated about its vertical pivot 26 to swing the arm or link 16 in the required direction to cause the sash 4 and other sashes coupled thereto to be moved inwardly toward closed position or opened according to the direction of rotative movement of the crank 13. When the arm or link 16 is swung, its outer end will slide back and forth along the bottom of sash 4 required, by means of the slidable connection established between the plate 18 and the guide strip 9. Since the pivoted sash 4 travels in an arc it is apparent that the link 16 must be capable of swinging upwardly or downwardly according to the direction of swing of the sash. The hinge 15 permits this up and down swing of the link 16 and the ball-and-socket connection between the outer end of the link 16 and the slide 18 allows this end of the link to position itself as required during the swinging movements of the sash.

When the sash is in its closed position, the arm or link 16 is disposed between the lower bar 8 of the sash and the top of the bottom bar 3 of the frame. To limit the swing of the arm or link 16, a stop 34 is provided on the plate 14, said stop abutting against a portion of the housing 10 when the arm is in its fully extended position, permitting the sash to be opened and lie at an angle of approximately 45 degrees.

While I have shown one embodiment of the invention, it is obvious that the same is not to be restricted thereto but is broad enough to cover all structures coming within the scope of the annexed claims.

What I claim is:

1. A sash-operating device for awning type windows comprising, a window frame, a sash pivoted in said frame on a horizontally disposed pivot located adjacent the top of the sash, the free lower edge of the sash being provided with a channel, an operating device including a housing attached to the inside of the frame, a rotative disk in said housing and mounted for rotative projection out of the housing, crank-operated gear means for rotating the disk, a link having one end pivotally attached by a horizontally disposed pivot to the disk, said link extending tangentially from the disk, the second end being secured by a ball-and-socket connection to a slide mounted for sliding movement in the channel on the lower edge of the sash.

2. A sash-operating device for awning type windows comprising, a window frame, a sash pivoted in said frame on a horizontally disposed pivot located adjacent to the top of the sash, the free lower edge of the sash being provided with a downwardly-directed channel strip, a sash-operating device including a housing attached to the inside of the window frame, a rotative toothed disk contained in said housing and mounted for rotative movement on a vertical pivot with a portion of the disk operative out of the housing, crank-operated gear means for engagement with the toothed portion of the disk for rotating said disk, a link having one end pivotally attached on a horizontal pivot only to the disk, said link extending from the disk and having a second end secured by a ball-and-socket connection to a slide mounted for sliding movement in the channel strip on the lower edge of the sash.

JOSEPH C. BANCROFT.
